TYPEWRITING MACHINE

Meigs W. Newberry, South Windsor, Conn., assignor to Underwood Elliott Fisher Company, New York, N. Y., a corporation of Delaware

Application April 21, 1942, Serial No. 439,889

19 Claims. (Cl. 197—63)

This invention relates to key-settable, margin-gaging mechanisms for typewriting machines, and more particularly to mechanisms of this character having provision for margin release and automatic restoration therefrom for normal line typing.

One of the objects of the invention is to provide an improved margin-release device for key-controlled release of the carriage from the normal limits of line-typing to permit typing beyond either margin, and adapted to be automatically reconditioned for gaging the normal typing line limits upon bringing the carriage back within the range of the limits; the improvements being related particularly to margin-gaging mechanisms having key-settable stops uniform throughout the range of carriage travel and positioned identically when set for gaging the margins.

The present invention constitutes mainly an improvement in the margin-gaging mechanism described and claimed in the copending application of Helmond, Serial No. 372,297, filed December 30, 1940. The present improvements afford a more simple structure by eliminating a number of the elements of the earlier mechanism, and otherwise materially simplify the mechanism, without sacrificing any of its practical operating characteristics.

A further improvement over the mechanism shown in said copending application is that of making provision for use of both primary and secondary margin-gaging stops; affording mechanism which permits of defining two stop positions for the carriage in each direction of travel, this provision being of practical advantage in typing operations such as involve the indenting or blocking in of the typed matter, paragraphing, marginal numbering of lines, etc.

The improved mechanism, having provision for both primary and secondary margin gaging, further provides means operable at will for rendering the stops for primary margin-gaging ineffective. Thus, the typist may select for continued use at will, either the primary stops gaging a shorter line or the secondary stops gaging a longer line.

The invention in certain respects constitutes a further improvement on the one described and claimed in the copending application of Helmond, Serial No. 341,420, filed June 20, 1940, now Patent No. 2,316,865, dated April 20, 1943 and is also an improvement on the mechanism shown in the U. S. patent to Dobson No. 2,196,790, dated April 9, 1940.

In the drawings:

Figure 1 is a front elevational view of the

margin-gaging mechanism of the invention, in the condition of typing a line between prescribed normal margins. To facilitate illustration, the view omits certain elements of the stop-restoring mechanisms,

Figure 2 is a sectional view taken on a fore-and-aft plane of the typewriter, showing the margin-stop mechanism in side elevation.

Figure 3 is a fragmentary exploded perspective, as viewed from the rear of the machine, showing the counter-stop, the associated margin-release and restoring mechanism, and the stop-setting mechanism.

Figures 4, 5, and 6 are fragmentary front elevations, showing the mechanism in various conditions of operation in releasing from the right-hand margin or line end for further typing; Figure 4 being the condition when the carriage is arrested at said margin and the margin-release key is initially depressed; Figure 5, when the release key has been fully depressed, and Figure 6, the condition during typing beyond the margin, and

Figure 7 is a fragmentary elevation of the mechanism as shown in Figure 6 condition but viewed from the rear of the machine.

Referring now to the drawings, and more particularly to Figures 1 and 2, the typewriting machine forming the illustrative embodiment of the invention includes a carriage 10 having end members 11 rigidly connected by means including a cross member or carriage rail 12 mounting the carriage for line-typing movement on trackways 13 supported on the main frame of the machine. The usual typing instrumentalities may be provided, of which type keys, not shown, are arranged to actuate type bars 14 to strike a work sheet on platen 15 on the carriage. The carriage is actuated in the letter-feed direction by the usual spring drum, not shown, under control of an escapement mechanism 16, wheel 17 of which may be reared to the carriage by a pinion 18 and carriage rack 19. The carriage may be advanced step by step in the conventional manner by the type bars 14 engaging and actuating a universal bar 20 connected to a rockable bail 21 pivoted at 22 and operatively connected at 23 to an escapement dog carrier 24 cooperative with the wheel 17 in the well-known manner. In consequence of each type-key operation and the resultant type-bar stroke, the carriage is advanced a letter space in line-typing direction so that the type characters are successively imprinted in a typing line on the work sheet on the platen.

A series of margin stops 25, which may be

identical in form throughout the range of carriage travel, are arranged at letter-space intervals on the carriage and are supported by a rack bar 26 secured at each end to the carriage. Each stop 25 is slideable in the rack bar for position-adjustment to or from an ineffective setting and projected position in which the lower end of the stop is disposed to engage a counterstop 27 during carriage travel. A detent spring yieldably holds the stop at said positions. The stop rack organization may be of any suitable arrangement such as that shown in my Patent No. 2,146,821, dated February 14, 1939.

Stop setting

The stop to be set is positioned at a setting station just to the left of the counterstop in its normal position, the stop being located at said station by appropriately positioning the carriage in its range of travel. A stop setter 28 has a setting finger 29 overlying a stop at said station, to set said stop when the setter is actuated by either of two key levers including a left-hand stop-setting key lever 30 and a right-hand stop-setting key lever 31. Whether set for left- or right-hand margin gaging, the stops are identically positioned, to move in a common path during travel of the carriage. In that only a single counterstop is employed for gaging both the right- and left-hand margins, means is provided by which any one stop being set may be adapted to gage either the right- or left-hand margin, depending on which of the key levers 30, 31 is operated. This is accomplished by causing the counterstop to be positioned at the appropriate side of the stop to be set, preparatory to setting the stop. This principle of operation in stop setting is described and claimed in the aforesaid application Serial No. 341,420, and, in combination with other features, forms part of the subject matter of the aforesaid application, Serial No. 372,297. Said mechanism is described herein in that it is combined with and forms part of the margin-release and restoring mechanism forming the subject matter of the present invention.

The shifting of the counterstop leftward of the stop-setting stations, preparatory to setting a right-hand or line-end stop, is effected by mechanism including a shift member 33. Adjacent its upper end, the counterstop 27 presents a broad portion 34 slidably retained between two lugs 35 of the shift member. A bracket 36, secured to the rear trackway 13 or other fixed portion of the machine, supports a pivot 37 on which the shift member 33 is pivoted intermediate its ends. The upper end of said shift member provides two laterally projecting lugs 38 which move in a slot of a cover member 39 on a housing 40 and cooperate with the ends of said slot to limit the extent of swinging movement of the shift member. The limits of counterstop shifting, determined by limiting the swing of the shift member, are such that a set stop, whether moving leftwardly or rightwardly toward the counterstop, is arrested at the same point. A spring 41 yieldably holds the shift member and, therefore, the counterstop 28 in the rightward position.

Leftward displacement of the counterstop is effected, as aforementioned, by correspondingly displacing the shift member 33, the latter being actuated by a roller 42 cooperating with a cam 43 on the lower portion of said shift member. The two stop-setting key levers 30, 31 are pivoted

on a rod 44 in a comb bar 45, see Figure 2, and are articulated at their rear ends to levers 46, 47, respectively, pivoted at 48 on a bracket 49 held on said comb bar. As shown best in Figure 3, lever 46 is articulated to the stop setter 28 and has a pin 59 projecting beneath lever 47, which lever carries the roller 42.

It will now be seen that when either key lever 30, 31 is actuated, the stop-setting finger 29 is pulled down and sets the stop 25 positioned at the setting station. Actuation of key lever 30 operates the stop setter directly through lever 46. Actuation of key lever 31 operates lever 47 which engages pin 59 and thus operates the stop setter

28. When key lever 30 for setting a left-hand stop is actuated, the counterstop remains stationary; that is, its position rightward of the setting station is maintained, so that the stop being set is set at the left side of the counterstop. However, when key lever 31 for setting a right-hand stop is actuated, the resultant movement of roller 42, coacting with cam 43, swings shift member 33 and thus causes the counterstop 27 to be shifted to the left of the setting station before the stop is actually set; so that when the stop is set, it is on the right side of the counterstop 27. In this manner, a stop being set may be adapted to gage either the left-hand or right-hand margin according to which of the key levers 30, 31 is operated.

A yieldable device is provided in the mechanism for setting a right-hand stop, to prevent damage to said mechanism by forceful operation, in the instance where a stop already set is adjacent the counterstop 27 at its left side, thus blocking proper shifting of the counterstop. This yieldable device is also included in the subject matter described and claimed in the copending application Serial No. 372,297. The device includes a spring 51 which urges lever 47 rightward; that is, in a direction opposite that in which roller 42 tends to move said lever because of the reaction of cam 43 thereon. Lever 47 has an elongate slot 52 cooperating with pivot 48, spring 51 tending to keep the leftward end of the slot against said pivot. When key lever 31 is operated and shifting of counterstop 27 is blocked by a set stop 25, as described, shift lever 33 is thus rendered immovable but roller 42 is allowed to ride down cam 43, nevertheless, in that spring 51 yields to allow lever 47 to shift leftwardly on its pivot. Upon release of key lever 31, spring 51 causes the elements to return to normal position, Figure 1. Spring 51 is of greater force than spring 41 so that in normal operation spring 41 will yield during actuation of shift lever 33, while spring 51 retains lever 47 in its normal rightward position.

Stop restoring

The mechanism for restoring any set stops to ineffective position may be of any known kind. In the embodiment illustrated, a key lever 53 is fulcrumed at its rear end on a bracket 54, see Figure 2, and, intermediate its ends, is articulated to a second lever 55 pivoted at 56 on a bracket 57 and flexibly connected to a stop-restoring member 58. The restoring member 58 is slidably retained in the cover plate 39 and is arranged so that its upper end engages set stops positioned at or adjacent to the setting station. Upon actuation of key lever 53, the restoring member 58 is raised to restore the set stop. A spring 59, Figure 1, restores the mechanism to quiescent condition.

Margin release mechanism

An improved margin release mechanism is herein provided to release the carriage for movement beyond the margins defined by the set stops. Upon actuation of a margin-release key lever 60, the counterstop 27 is retracted to a position in which it is clear of the set stops 25 and, thereafter, a holding device is rendered effective to retain the counterstop retracted. When the typing beyond the margin is completed and the carriage is again restored to position for typing between the margins, this carriage movement brings a set stop into coaction with the holding device and causes the latter to release the counterstop so that same resumes its effective position in the path of the set stops.

This holding device comprises mainly a cam 62 which, as shown best in Figure 3, is rotatably mounted on the shift lever 33 by a stud 63 journaled in a bearing 64. Cam 62 has a series of cam faces at its lower portion, that cooperate with a roller 66 carried on the counterstop 27 to hold the counterstop retracted or release same into the path of the stops 25. In the various phases of operation, the cam 62 may assume any one of three positions in each of which one of three cam teeth 67, 68, and 70 thereon is projected upwardly substantially in alignment with the upper end portion of the counterstop, see Figures 1 and 6.

Two detent arms 71, 72, acting mainly as a centering device for cam 62, are pivoted on the shift member 33 and are urged toward each other by a spring 73. A pin 74 on the cam 62 projects between said arms which, under the force of spring 73, yieldably hold the cam in a medial position, Figure 2, with the pin 74 pressed between flats at the upper arm ends. When the cam 62 is angularly displaced, either leftwardly or rightwardly to a position defined by engagement of either tooth 67, 68 with the corresponding lug 35, the cam pin 74 seats in a notch 75 of the corresponding detent arm, see Figure 7. Under such condition, the other detent arm acts only to hold the spring 73, said arm resting on the bearing 64. The notches 75 are shaped so as to allow pin 74 to move with the cam to displaced position, without tending to re-center the cam after it has been initially displaced from its medial position an appreciable degree.

The margin-release key lever 60 is pivoted intermediate its ends on the comb bar 47 and is articulated at its rear end to a second lever 76 pivoted at 48, a pin 77 on the second lever engaging the counterstop 27 in a slot 78 thereof. Said counterstop is slidably retained at its upper portion, between the lugs 35 against lateral displacement and, between the restoring member 53 at the front and cam 62 at the rear, against fore-and-aft displacement. As shown in Figure 1, lever 76 projects through a slot in a side member of the machine main frame and bottoms in said slot in quiescent position, a spring 84 urging lever 76 and key lever 60 to quiescent position. A spring 86, anchored on the bracket 36, urges counterstop 27 upwardly to its normal position projecting into the path of the set stops, in which position the bottom of slot 78 is against pin 77, lever 76 being at rest against the bottom of the main frame slot.

The mentioned faces of the cam 62 include a medially disposed recess 81 and left and right, oppositely inclined faces 82, 83. The recess 81 is so spaced from the cam axis 63 as to allow the counterstop to project into the stop path. The inclined faces 82, 83 are spaced farther from

the cam axis so as to hold the counterstop retracted when the cam 62 has been swung to either side of its medial position. A high point is provided between each cam face 82, 83 and the recess 81 to function as a detent for the cam, in cooperation with roller 66.

When the margin-release key lever 60 is pressed, the extent of the resultant retraction of counterstop 27 is limited by engagement of lever 76 with an adjustable stop such as a screw 79 on the main frame, Figure 1. This retraction, although sufficient to put counterstop 27 out of the stop path, does not, however, bring roller 66 entirely out of recess 81, for reasons hereinafter made clear.

Operation of margin release

When margin release is desired, the carriage is usually at either margin limit, as defined by the set stops. When the carriage is at its rightward limit or line-start position, the left margin stop is engaged with the counterstop, the latter remaining in its normal position, Figure 1. In releasing the carriage from line-start position, after retracting the counterstop by pressing key lever 60, the carriage is moved further rightward, as is the usual practice, to position same in readiness to begin the typing at the new line-start. During this additional carriage movement to the new line-start position, the left-hand set stop 25 moves rightwardly past the retracted counterstop and, engaging the medial tooth 70 of cam 62, causes said cam to be rotated an initial degree. In that roller 66 has been only partly withdrawn from recess 81, the high point of the cam face adjacent said recess now cams the roller further downwardly until said high point is beyond the axis of said roller. The roller 66, under influence of spring 88, now co-acts with inclined face 83 of the cam and causes further cam rotation until the cam tooth 68 engages the right-hand lug 35. In that stop screw 79 prevents full withdrawal of the roller 66 from the recess 81, said roller, after riding over the high point of the cam, will move upwardly with the counterstop 27 under influence of spring 80 and will therefore coact fully with the cam face 83 to complete the cam rotation. In other words, the stop 79 limits counterstop retraction to such an extent that roller 66 cannot be lowered, by the release key lever, below the position thereof shown in Figure 7. The additional movement necessary to allow the high point of the cam to pass over the roller, is afforded at the pin-and-slot connection 77, 78.

The operation of the mechanism to release from the right-hand or line-end margin is illustrated in Figures 4, 5, and 6. When the carriage is at its leftward limit, that is, at the normal line end defined by the right-hand margin stop, the counterstop 27, the shift lever 33, and the cam 62 thereon have been shifted bodily leftward to the position shown in Figure 4, limited by lug 38 having engaged the end of the slot in cover member 39. When the margin release key lever 60 is actuated, counterstop 27 is thus retracted and slides down the set stop 25 with which it is engaged. Just prior to sliding off said stop, the condition of the mechanism is that shown in Figure 4, it being noted that the medial cam tooth 70 remains in engagement with the stop. As soon as counterstop 27 rides off the stop, the mechanism assumes the condition shown in Figure 5, that is, the counterstop and shift member 33 have been swung rightward bodily by spring 41 until

the other lug 38 engages the opposite end of the slot in cover member 39. During this swinging movement, however, tooth 70 has remained in engagement with the stop, and, therefore, the relative displacement of the cam pivot 63 by the rightward shifting of member 33 has caused cam 62 to be initially rotated to the Figure 5 position. It will be observed that the carriage is now released and typing beyond the line end may now be done. The key lever 60 may now be released in that the counterstop is now held down by the high point of the cam being engaged with the roller. The subsequent typing beyond the normal line end further rotates cam 62, rotation of which is completed to the Figure 6 position by the coaction of roller 66 with the cam face 82, assisted by the 10 15 20 25 30 35 40 45 50 55 60 65 70 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 arm 88. When the counterstop 27 is in the position shown in Figure 1, as during the usual typing, the locking lever 89 has its forward end to one side of the arm 88; but upon shifting the counterstop incident to arresting the carriage at line end, the lever 89 is moved into position abutting arm 88 and thus obstructs vibration of the universal bar 20. Upon returning the carriage or in operating the margin release, in either case allowing the counterstop 27 and shift member 33 to return to the rightward position, the locking lever is accordingly swung to a position clear of arm 88.

Although in this application there is specifically described one embodiment which the invention may assume in practice, it will be understood that same is shown for the purposes of illustration and that the invention may be modified and embodied in various other forms without departing from its spirit or the scope of the appended claims.

What is claimed is:

1. In a typewriter having a carriage movable in letter-space increments; a margin-gaging mechanism including a group of uniform stops on the carriage, arranged at slightly spaced intervals and selectively settable to corresponding effective positions in alignment with each other; a first set stop and a second set stop of said group being adapted to determine successive stopping points for the carriage; a first counterstop arranged in relation to the set stops to bar travel of the carriage at the first point; means adapted to effect a change in the relationship between the first counterstop and the first set stop to permit movement of the carriage beyond the first point; a second counterstop arranged in relation to the set stops to permit travel of the carriage; and means, operable during carriage travel beyond the first point, to effect a change in the relationship of said second counterstop and said second set stop to bar travel of the carriage at the second point.

2. In a typewriter having a carriage movable in letter-space increments; a margin-gaging mechanism including a group of uniform stops on the carriage, arranged at slightly spaced intervals and selectively settable to corresponding effective positions in alignment with each other; a first set stop and a second set stop of said group being adapted to determine successive stopping points for the carriage; a first counterstop arranged in relation to the set stops to bar travel of the carriage at the first point; means adapted to effect a change in the relationship between the first counterstop and the first set stop to permit movement of the carriage beyond the first point; a second counterstop arranged in relation to the set stops to permit travel of the carriage; and means, operable by the first set stop during carriage travel beyond the first point, to effect a change in the relationship of said second counterstop and said second set stop to bar travel of the carriage at the second point.

3. In a typewriter having a carriage movable in letter-space increments; a margin-gaging mechanism including a first stop and a second stop on the carriage, adapted to determine successive stopping points for the carriage; a first counterstop arranged in relation to the stops to bar travel of the carriage in one direction at the first point; means adapted to effect a change in the relationship between the first counterstop and the first stop to permit travel of the car-

riage beyond the first point; a second counterstop arranged in relation to the stops to permit travel of the carriage; means, operable during the carriage travel beyond the first point, to 5 maintain the changed relationship of the first counterstop and first stop, and to effect a change in the relationship of said second counterstop and the second stop to bar travel of the carriage in the one direction at the second point; the last 10 said means being operable, upon travel of the carriage in an opposite direction past the first point, to restore the original relationships between the first counterstop and the first stop and between the second counterstop and the second stop.

4. In a typewriter having a carriage movable in letter-space increments; a margin-gaging mechanism including a group of uniform stops on the carriage, arranged at slightly spaced intervals and selectively settable to corresponding effective positions in alignment with each other; a first set stop and a second set stop of said group being adapted to determine successive stopping points for the carriage; a first counterstop arranged to engage the first set stop to bar travel of the carriage at a first point; means to render said first counterstop ineffective to permit carriage travel beyond said first point; a second counterstop arranged to clear the set stops; and means, actuatable by the first set stop during travel of the carriage beyond the first point, to render said second counterstop effective for engagement by said second set stop to bar carriage travel at the second point.

5. In a typewriter having a carriage movable in letter-space increments; a margin-gaging mechanism including a first stop and a second stop on the carriage, adapted to determine successive stopping points for the carriage; a first counterstop arranged to engage the first stop to bar travel of the carriage in one direction at a first point; means to render said first counterstop ineffective to permit carriage travel beyond said first point; a second counterstop arranged to clear the stops; means, actuatable by the first stop during travel of the carriage beyond the first point, to maintain said first counterstop ineffective and to render said second counterstop effective for engagement by said second set stop, 40 to bar carriage travel in the one direction at the second point; the last said means being operable, upon travel of the carriage in an opposite direction past the first point, to render said first counterstop again effective and condition said 55 second counterstop to again clear the stops.

6. In a typewriter having a reciprocatory carriage; a margin-gaging mechanism including a first stop and a second stop on the carriage, defining successive stopping points for the carriage; a first counterstop arranged to engage the first stop to bar carriage travel at a first point; a second counterstop arranged to clear the stops; and key-controlled means to disable the first counterstop, and conditionable by the first stop during carriage travel in one direction, to render the second counterstop effective and to hold the first counterstop disabled; said key-controlled means being conditionable by the first stop, during carriage travel in an opposite direction, to disable said second counterstop and restore said first counterstop for stop-engagement.

7. In a typewriter having a reciprocatory carriage; a margin-gaging mechanism including a first stop and a second stop on the carriage, defining successive stopping points for the carriage;

a first counterstop arranged to engage the first stop to bar carriage travel at a first point; a second counterstop arranged to clear the stops; key-controlled means to disable the first counterstop, and conditionable by the first stop during carriage travel in one direction, to render the second counterstop effective and to hold the first counterstop disabled; said key-controlled means being conditionable by the first stop, during carriage travel in an opposite direction, to disable said second counterstop and restore said first counterstop for stop-engagement; means yieldably holding said key-controlled means in non-operative condition; and means to hold said key-controlled means in operative condition.

8. In a typewriter having a reciprocatory carriage, a margin-gaging mechanism including; a first stop and a second stop on the carriage near each end thereof, defining successive stopping points for the carriage during its travel in either direction; a first counterstop arranged for engagement by the two first stops to bar carriage travel in either direction at the first points; key-controlled means to disable said first counterstop to permit carriage travel beyond one or the other first point; said key-controlled means including secondary counterstop means ineffective to bar carriage travel and conditionable by the first stops during carriage travel beyond either first point to hold said first counterstop disabled and to render said secondary counterstop means effective to engage one or the other second stop depending on the direction of carriage travel, to bar carriage travel at a second point; said key-controlled means being conditionable by the first stops, during carriage travel back from beyond the first point, to disable said secondary counterstop means and restore said first counterstop for stop-engagement.

9. In a typewriter having a reciprocatory carriage, a margin-gaging mechanism including; a first stop and a second stop on the carriage near each end thereof, defining successive stopping points for the carriage during its travel in either direction; a first counterstop arranged for engagement by the two first stops to bar carriage travel in either direction at the first points; key-controlled means to disable said first counterstop to permit carriage travel beyond one or the other first points; said key-controlled means including secondary counterstop means ineffective to bar carriage travel and conditionable by the first stops during carriage travel beyond either first point to hold said first counterstop disabled and to render said secondary counterstop means effective to engage one or the other second stop, depending on the direction of carriage travel; means yieldably holding said key-controlled means in non-operative condition; and means to hold said key-controlled means in operative condition.

10. In a typewriter having a reciprocatory carriage; a margin-gaging mechanism including; a first stop and a second stop on the carriage, defining successive stopping points for the carriage; a first counterstop arranged to engage the first stop to bar carriage travel at a first point; means to disable said first counterstop to permit carriage travel beyond the first point; and a rotatable member actuatable by the first stop and adapted to releasably hold the first counterstop disabled, said rotatable member including a second counterstop position to clear the stops; the arrangement being such that rotation of said member, during carriage travel in one direction

beyond the first point, effects holding of the first counterstop disabled and positioning of the second counterstop to engage the second stop, and rotation of said member, during carriage travel in the opposite direction from beyond the first point, effects release of the first counterstop and return of the second counterstop to stop-clearing position.

11. In a typewriter having a reciprocatory carriage; a margin-gaging mechanism including a first stop and a second stop on the carriage, defining successive stopping points for the carriage; a first counterstop arranged to engage the first stop to bar carriage travel at a first point; means to disable said first counterstop to permit carriage travel beyond the first point; and a rotatable cam actuatable by the first stop and adapted to hold said first counterstop disabled, said cam including a second counterstop positioned to clear the stops; travel of the carriage in one direction beyond the first point causing said cam to hold the first counterstop disabled and to position the second counterstop for engagement by the second stop, and travel of the carriage in the opposite direction from beyond the first point causing release of the first counterstop and return of the second counterstop to stop-clearing position.

12. In a typewriter having a reciprocatory carriage; a margin-gaging mechanism including a first stop and a second stop on the carriage, defining successive stopping points for the carriage; a first counterstop arranged to engage the first stop to bar carriage travel at a first point; means, yieldably held in non-operative condition, to disable said first counterstop to permit carriage travel beyond the first point; and a rotatable member actuatable by the first stop and including means, rendered effective upon rotating said rotatable member, to hold the first counterstop disabled, said member including a second counterstop positioned to clear the stops; the arrangement being such that travel of the carriage in one direction beyond the first point causes said member to hold the first counterstop disabled and to position the second counterstop for engagement by the second stop; means being provided to hold said disabling means in operated condition, whereby the first counterstop may be held disabled so that the carriage may travel past the first point, to be stopped at the second point.

13. In a typewriter having a carriage movable in letter-space increments; a margin-gaging mechanism including a first stop and a second stop on the carriage, defining successive stopping points for the carriage; a first counterstop urged to position to intercept the first stop to bar carriage travel at a first point; means to retract said counterstop to clear the stops to permit carriage travel beyond the first point; a cam follower on said counterstop; and a rotatable cam cooperable with said follower and having portions engageable by said stops; said cam being adapted, upon being rotated, to hold said counterstop retracted; said cam presenting a second counterstop positioned to clear said stops and adapted to be positioned, upon rotating said cam for holding the first counterstop, to intercept the second stop and thus bar carriage travel at the second point.

14. In a typewriter having a reciprocatory carriage; a margin-gaging mechanism including a first stop and a second stop near each end of the carriage, defining successive stopping points for the carriage during travel in one direction or the other; a first counterstop urged to stop-inter-

cepting position and arranged between said first stops to limit carriage travel in either direction at a first point; means to retract said counterstop to a position clear of the stops to permit carriage travel beyond the first point; a cam follower on said counterstop; and a rotatable cam actuatable by either of said first stops and cooperable with said follower; said cam being adapted, upon being rotated in one direction or the other, depending on the direction of carriage travel, to hold said counterstop retracted; said cam presenting two second counterstops each positioned to clear said stops and adapted to be positioned, upon rotation of said cam in one direction or the other, to intercept one or the other second stop, depending on the direction of carriage travel, and thus bar carriage travel at a second point.

15. In a typewriter having a reciprocatory carriage; a margin-gaging mechanism including a stop on the carriage; a retractable counterstop urged to effective position for intercepting the stop to gage a normal line end of carriage travel; means to retract said counterstop to clear the stop, to permit carriage travel beyond the normal line end; a cam follower on said counterstop; a rotatable cam having a series of faces on which said follower is seatable, the faces being differently spaced from the cam axis to gage the counterstop at stop-clearing and stop-intercepting positions; said cam being actuatable by the stop during carriage travel in one direction or the other, to rotate the cam to the different counterstop-engaging positions; and means limiting actuation of said counterstop-retracting means substantially to an extent preventing movement of said follower beyond its position for gaging the counterstop at stop-clearing position.

16. In a typewriter having a reciprocatory carriage; a margin-gaging mechanism including two stops on the carriage, one near each carriage end; a retractable counterstop urged to effective position for intercepting the stops to gage the normal line ends of carriage travel; means to retract said counterstop to clear the stops to permit carriage travel beyond either normal line end; a cam follower on said counterstop; a rotatable cam having a series of faces on which said follower is seatable, including a medial face to gage the counterstop at stop-intercepting position and two offset faces, one at each side of said medial face, for gaging the counterstop at a stop-clearing position; said cam being actuatable by the stops during carriage travel in one direction or the other to rotate the cam to the different counterstop-gaging positions; and means limiting actuation of said counterstop-retracting means substantially to an extent preventing movement of said follower beyond its position assumed in gaging the counterstop at stop-clearing position.

17. In a typewriter having a carriage; a margin-engaging mechanism including a first stop and a second stop near one carriage end; a first counterstop urged to effective position for intercepting the first stop; means to retract said counterstop to clear the stops; a rotatable cam having a series of faces cooperable with the counterstop, the faces being offset from each other to gage the counterstop at stop-clearing and stop-intercepting positions and having a high

point therebetween; said cam being actuatable by the first stop during carriage travel in one direction or the other, to rotate the same to the different counterstop-gaging positions; said cam including a second counterstop arranged to clear the stops when the cam gages the first counterstop at stop-intercepting position, and positioned for interception of the second stop when the cam gages the first counterstop at stop-clearing position; and means limiting actuation of said counterstop-retracting means substantially to an extent preventing movement of said counterstop beyond its stop-clearing position.

18. In a typewriter having a reciprocatory carriage, a margin-gaging mechanism including; a plurality of settable stops arranged at slightly spaced intervals along the carriage; key-actuatable means operable at a station to individually set any of said stops positioned at the station; a first stop and a second stop set near each carriage end, defining successive stopping points for the carriage in each direction of travel; a first counterstop arranged for engagement by the two first stops to bar carriage travel at the first points; key-operable means to move said counterstop to stop-clearing position to permit carriage travel beyond either first point; means mounting the counterstop for shifting in the direction of carriage travel between limits close to each side of the setting station; a member shiftable with the counterstop; a cam actuatable by either of the said first stops and rotatably mounted on said member; said cam, when rotated to a leftward or rightward position incident to carriage travel beyond a first point, being adapted to hold the counterstop in stop clearing position; and normally ineffective second counterstop means on said cam, rendered effective upon rotating said cam incident to the carriage travel beyond a first point, to intercept the corresponding second stop.

19. In a typewriter having a reciprocatory carriage, a margin-gaging mechanism including; a plurality of settable stops arranged at slightly spaced intervals along the carriage; key-actuatable means operable at a station to individually set any of said stops positioned at the station; a first stop and a second stop set near each carriage end defining successive stopping points for the carriage in each direction; a first counterstop arranged for engagement by the two first stops to bar carriage travel at the first points; key-operable means to move said counterstop to stop-clearing position to permit carriage travel beyond either first point; means mounting the counterstop for shifting in the direction of carriage travel between limits close to each side of the setting station; a member shiftable with the counterstop; a cam actuatable by either of the said first stops and rotatably mounted on said member; said cam, when rotated to a leftward or rightward position incident to carriage travel beyond a first point, being adapted to hold the counterstop in stop clearing position; said cam having means cooperative with said member to limit cam rotation to said positions; and normally ineffective second counterstop means on said cam, rendered effective upon rotating said cam incident to the carriage travel beyond a first point, to intercept the corresponding second stop.
